Primary Examiner — Sheryl Lane
Assistant Examiner — Ieisha N Price(57) **CLAIM**

The ornamental design for a digging tool, as shown and described.

DESCRIPTION

FIG. 1 is a top, front perspective view of a digging tool showing my new design;

FIG. 2 is a front view of the digging tool;

FIG. 3 is a rear view of the digging tool;

FIG. 4 is a left side view of the digging tool;

FIG. 5 is a right side view of the digging tool;

FIG. 6 is a top view of the digging tool; and,

FIG. 7 is a bottom view of the digging tool.
